(57) **CLAIM**

The ornamental design for semiconductor power module for vehicles as shown and described.

DESCRIPTION

1. Semiconductor power module for vehicles

1.1 : Perspective

1.2 : Top

1.3 : Bottom

1.4 : Front

1.5 : Back

1.6 : Right

1.7 : Left

(Continued)

The broken lines illustrate portions of the claimed semiconductor power module that form no part of the claimed design.
